UNITED STATES PATENT OFFICE.

LEON HEITMAN, OF NEW YORK, N. Y.

FLOOR-SCRUBBING MACHINE.

Application filed February 5, 1923. Serial No. 616,887.

To all whom it may concern:

Be it known that I, LEON HEITMAN, a citizen of Austria, residing at New York, in the county of Bronx and State of New York, have invented certain new and useful Improvements in Floor-Scrubbing Machines, of which the following is a specification.

This invention relates to improvements in floor scrubbing machines and has as one of its objects to provide a manually operable wheeled tank having means for moistening the floor to be cleaned preliminary to the operation of brushes thereover.

Another purpose is to produce a mechanism having both a reciprocating scrub brush and a rotary brush, both being selectively mounted and actuated by the movement of the machine.

A further aim is in the provision of a mop, also driven by the mechanism, provision being made for squeezing the same at intervals during its operation.

These and other like objects are attained by the novel construction and combination of parts hereinafter described in detail and shown in the accompanying drawing, and in which:

Figure 1 is a plan view showing an embodiment of the invention.

Figure 2 is a side elevational view of the same.

Figure 3 is a transverse sectional view taken on line 3—3 of Figure 1.

Figure 4 is a similar sectional view taken on line 4—4 of Figure 1.

Figure 5 is a longitudinal sectional view taken on line 5—5 of Figure 1.

Fig. 6 is a sectional view showing the rotary brush mounting.

The apparatus consists of a rectangular tank, designated by the numeral 15, on which is a fixed cover plate 16.

A shaft 17 passes through the tank, the same being journaled in bearings 18 fixed within, its extending ends being mounted in wide-faced wheels 19 of such diameter as to cause the tank to clear the floor.

Fixed on the cover to extend upward and rearwardly is a propelling handle 20 and in the rear wall of the tank is an inlet or filler nozzle 21, there being a faucet 22 below by which the tank can be drained.

Near the front of the tank, on each side, are nipples engaged in elbows communicating by horizontal pipes with another pair

of elbows having between them a pipe 23 extending longitudinally in advance of the front wall of the tank and containing perforations 24 permitting the water to escape and moisten the floor.

Fixed alongside one of the wheels 19 is a bevel gear 25 meshing with a pinion 26 revolubly mounted on a post 27 fixed in the cover plate 16, the pinion carrying a rotatable stud 28 drilled transversely to receive a rod 29 which can be held in adjustment by a clamp screw 30.

A spur gear 31 is rotatably mounted on the cover plate 16 near its center and has a raised central portion containing an undercut slot 32 in which is slidably engaged the base of a stud 33 drilled to receive the rod 29 and which may be clamped in position by the screw 34, the device being so arranged that as the wheels 19 revolve, the gear 31 will be turned reciprocatively.

Meshing with the gear 31 is a segment 35 pivoted on a stud 36 in the cover plate and having an oppositely extending cylindrical projection 37.

Holes are provided through the segment and cover plate respectively to receive a locking pin 38 when required.

A socket 39 is engageable with the cylindrical element 37 and may be secured in its two adjusted positions relative to it by a locking pin 40.

Formed with the socket is a plate extension 41 to which is attached a rectangular scrubbing brush 42 in such manner as to be oscillated by it when the gearing is in operation.

Attached to the opposite side of the plate 41 is a bar 43 having downturned ends 44 in which is rotatably journalled a shaft 45 having mounted on its ends wheels 46 and 47, the latter having alongside it a spur gear 48.

This gear meshes with another gear 49 fixed on the end of a shaft 50 carried on the brackets 51 secured to the sides of the tank 15.

The shaft 50 is driven by a gear 52 meshing with a mate 53 fixed besides a sprocket wheel 54, over which is trained a chain 55 driven by a sprocket 56 fixed on the hub of the gear 25.

The sprocket wheel 54 and gear 53 are fixed at one end of a shaft 57, extending through the front of the tank.

Also fixed on the shaft 50 is an elongated

hub 59 carrying a pair of opposed mop elements 60, which as they are rotated, pass over the lower front wall 58 of the tank and are engaged between a roll 61 mounted on the spindle 57 and a like roll 62 mounted on the spindle 63 movable vertically in slots 65 in the tank.

The upper roll is held normally depressed by flat springs 66, this roll being raised at 10 each partial revolution of the mop 60 by pairs of double cams 67 fixed on the spindle 57, this device compressing the mops and squeezing the water to fall into the tank, being automatic in their action.

15 Mounted loosely on the axle 45 is a sleeve member 45' secured to which is a split hub 68 carrying a cylindrical brush 69, the sleeve member having at one end a gear 70 driven by a pinion 71 which also meshes with an 20 internal gear 72 formed interiorly of and concentric to the gear 48, thus causing the brush to rotate in a clock-wise direction as the apparatus is trundled over a floor.

In the several figures the revolving brush 25 is shown as in position for operation, at which time the screw 34 will be slackened allowing the rod 29 to play idly through the stud, and the locking pin 38 is inserted to prevent operation of the segment.

30 When it is desired to use the brush 42, the pin 40 is withdrawn, allowing the plate 41 to be reversed, bringing the revolving brush, wheels 46 and 47, together with their attached parts uppermost, the pin 40 replaced, 35 the pin 38 removed and the rod 29 secured in the studs so as to transmit motion to the brush as will be apparent.

The mop 60 not only makes contact with

the revolving brush 69 when it is in its operative position for the purpose of cleaning 40 the mop, but wipes the floor behind either of the brushes as it is at all time in operating position.

From the foregoing it will be seen that a 45 positive acting device has been disclosed, capable of effectually performing all of the several objects set forth.

Having thus described my invention, what I 50 claim as new and desire to secure by Letters Patent, is:—

A floor scrubbing machine comprising in combination with a wheeled tank, means for dispensing the contents thereof, and a cylindrical brush adapted to be rotated by the wheels of the tank in an opposite direction 55 to said wheels, of a rotatable mop composed of a single pair of flexible, textile, oppositely disposed elements arranged parallel to the axis of said brush, each of said elements periodically engaging the periphery of the 60 brush, said tank having an opening in its wall adjacent said mop and through which the mop elements are projected, a roll within the tank and rotatable with a supporting 65 spindle, elliptical cams carried at the ends of the spindle, a superposed second roll operating in slots in the tank walls and having contact surfaces engaging said cams, springs urging said second roll downwardly, whereby 70 said rolls are successively opened and closed to receive and squeeze said mop elements on being projected through the tank opening.

In witness whereof I have affixed my signature.

LEON HEITMAN.
